UNITED STATES PATENT OFFICE.

FREDERICK C. SIXT, OF CLEVELAND, OHIO, ASSIGNOR TO THE CHANDLER & PRICE COMPANY, OF CLEVELAND, OHIO, A CORPORATION OF OHIO.

INKING MECHANISM FOR PRINTING PRESSES.

Application filed June 27, 1921. Serial No. 480,524.

To all whom it may concern:

Be it known that I, FREDERICK C. SIXT, a citizen of the United States, and a resident of Cleveland, county of Cuyahoga, and State of Ohio, have invented a new and useful Improvement in Inking Mechanism for Printing Presses, of which the following is a specification, the principle of the invention being herein explained and the best mode in which I have contemplated applying that principle, so as to distinguish it from other inventions.

The present improvements relate more particularly to so-called vibrator rollers for distributing the ink on the rollers that directly contact with the disk and form in order to transfer ink from such disk to form. While, illustrated in connection with so-called platen printing presses, it will be understood that my improved inking mechanism is not necessarily limited to this particular type of press.

Such vibrator roller is ordinarily mounted above and in contact with a pair of inking rollers proper so as to derive its rotative movement from the latter, and means are provided to simultaneously impart to said vibrator roller a movement longitudinal of the axes of such other rollers, hence the name. One object of the present invention is to provide improved bearings for the vibrator roller whereby it may be held in properly centered relation transversely of the two inking rollers with which it thus contacts; and another object is to provide a simple and compact device for causing the vibratory movement of the roller in question without requiring any special gearing or driving mechanism.

To the accomplishment of the foregoing and related ends, said invention, then, consists of the means hereinafter fully described and particularly pointed out in the claims, the annexed drawing and the following description setting forth in detail certain mechanism embodying the invention, such disclosed means constituting, however, but one of various mechanical forms in which the principle of the invention may be used.

In said annexed drawing:

Fig. 1 is a side elevation of a portion of a platen printing press, showing the form-supporting member, the inking disk and the rollers that co-operate therewith; Fig. 2 is a broken plan view of my improved vibrator

roller; Fig. 3 is a side elevation of one of the carriages in which said roller, along with the two inking rollers proper wherewith it co-operates, is mounted; Fig. 4 is a central longitudinal section of one end of said vibrator roller and corresponding mounting, the plane of the section being indicated by the line 4—4, Figs. 2 and 3; and Fig. 5 is a similar section of the other end of the roller with an end elevation of the corresponding mounting.

The general construction of the press, so far as illustrated in Fig. 1, will require only brief description. The bed 1, supports the form, that constitutes the printing surface, on the more or less vertical portion 2, and a disk 3, to which ink is supplied by any suitable means, not shown, so that as the rollers 4 travel across such disk and then across the form, the necessary amount of ink will be transferred to the latter. Rollers 4 are shown as three in number, the forward one having its ends attached to the hook-like extremities of the single saddles 5, of which one of course only appears in Fig. 1, while the two remaining rollers have their ends similarly attached to the double saddles 6, said saddles being mounted in the roller frames 7, one on each side of the bed 1.

Mounted on top of each saddle 6, as best shown in Fig. 3, is a journal box 10, in which is journaled the corresponding end of a rod or spindle 11 that is disposed above the axes of the two rollers 4 and approximately midway therebetween. Each box 10 is removably held by means of a pivotal plate 12 in a suitable recess formed in the upper face of a transverse member 13 that is held in place on the corresponding saddle 6 by means of two bolts 14 passing through elongated apertures 15 adjacent the respective ends of said member. Compression springs 16 surround said bolts and bear down on the ends of the member 15, the degree of pressure being adjustable by means of nuts 17 on the upper ends of the bolts, as will be readily understood. As a result of the foregoing constructions it will be seen that the members 15 are not only free to shift longitudinally of the respective saddles, but also vertically, thus allowing the necessary amount of freedom to the boxes 10 whereby the roller 20, supported on the spindle 11, next to be described, may "find" itself, i. e., bear uniformly upon the two rollers 4.

110

At its one end (the left as shown in Figs. 2, 4 and 5 of the drawing), roller 20 is provided with a collar 21 that is both rotatably and longitudinally movable on said spindle 11, while at its other end said roller is provided with an internally threaded nut 22 that engages with an externally threaded sleeve 23 non-rotatably secured to spindle 11 by means of a pin 24, a collar 25 fixed to said spindle at the inner end of the sleeve serving additionally to hold the same against longitudinal movement. Said threaded sleeve 23 projects a short distance beyond nut 22 and the corresponding end of roller 20 when the latter is in the extreme right-hand position, and in this position a stop 26 on said nut engages with a pin 27 that projects radially from said sleeve. The inner end of nut 22 is provided with a reversely directed stop 26^a that is adapted to engage with a corresponding radially projecting pin 27^a on collar 25, when the nut, by reason of rotation of the roller 20, has been moved to the inner end of threaded sleeve 23.

The outer end of sleeve 30 is also formed with one or more beveled teeth 28 that are adapted to engage corresponding notches 29 in a second sleeve 30 interposed between such end and the adjacent box 10. This last-mentioned sleeve is free to partake of limited movement longitudinally of spindle 11, but is held against rotation with respect to said spindle by means of a key 31 projecting inwardly from box 10 and engaging a notch 32 in the adjacent end of said sleeve. The latter is furthermore hollowed out for a portion of its length to form a housing for a compression spring 33, the outer end of which appears against said box 10 so as to normally press said sleeve 30 towards threaded sleeve 23.

From the foregoing construction it will be seen that with the parts in the position shown in Figs. 2 and 4, i. e., when the stop 26 on nut 22 strikes the pin 27 on threaded sleeve 23, the latter will be caused to revolve on the roller 20, and spindle 11 will at the same time be caused to revolve in journal box 10, such rotation of the parts in question causing the sleeve 30 to be longitudinally displaced outwardly, i. e. to the right, as tooth 28 rides out of notch 29. Such rotation may occur through one or more revolutions without affecting the mode of operation just described. Upon reversal of rotation of roller 20 the direction of the thread on sleeve 23 is such as to carry stop 26 clear of pin 27, and thus leave said roller free to revolve and at the same time move longitudinally of the axis of spindle 11 until stop 26^a engages the pin 27^a on collar 25. Then the same action with respect to sleeve 30 will occur as before.

Depending upon the length of threaded sleeve 23, it will be seen that any amount

of vibratory, i. e., longitudinal movement, of roller 20 may be secured, and when the limit of such movement in either direction is reached the roller will continue to rotate without further longitudinal movement. It will also be seen that the roller 20 is at all times held properly centered against the rollers 4 wherewith it contacts, and under a uniform pressure throughout its length, by reason of the floating mounting of the boxes 10, in which the ends of spindle 11 are journaled. Such boxes, furthermore, may be readily lifted out and the vibratory roller entirely removed by simply swinging the clamps 12 out of the way, said clamps being normally secured in place by wing nuts 34.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. In mechanism of the character described, the combination of a pair of inking rollers adapted to contact with the inking disk and form of a printing press, saddles for the respective ends of said rollers, an ink-distributing roller mounted above and in contact with said first-named rollers, and mountings for the ends of said ink-distributing roller, including a transverse member on each of said saddles provided with a bearing for the corresponding end of the spindle of said roller, said member being formed with elongated slots, bolts on said saddle passing through such slots, and springs on said bolts pressing downwardly on said member, whereby the latter is free to move both transversely and vertically relatively to said saddle.

2. In mechanism of the character described, the combination of a pair of inking rollers adapted to contact with the inking disk and form of a printing press, saddles for the respective ends of said rollers, a spindle rotatably journaled at its respective ends on said saddles, an ink-distributing roller mounted on said saddle so as to contact with said first-named rollers, an externally threaded sleeve fixedly secured to said spindle, an internally threaded collar on said roller engaging said sleeve, elements carried by said spindle and roller, respectively, adapted to interengage when said collar reaches either end of said sleeve and thereby non-rotatively lock said roller to said spindle, and a second sleeve on said spindle between the outer end of said first sleeve and the adjacent saddle, said second sleeve being longitudinally movable of but held against rotation with said spindle, and means housed within said second sleeve pressing the same against said

first sleeve for holding said spindle against rotation until said interlocking elements upon the roller and spindle become engaged at either end of the line of travel of said roller.

5. In mechanism of the character described, the combination of a pair of inking rollers adapted to contact with the inking disk and form of a printing press, saddles for the 10 respective ends of said rollers, a spindle rotatably journaled at its respective ends on said saddles, an ink-distributing roller mounted on said saddle so as to contact with said first-named rollers, an externally threaded sleeve fixedly secured to said spindle, an internally threaded collar on said roller engaging said sleeve, elements carried by said 15 spindle and roller, respectively, adapted to

interengage when said roller reaches either end of said sleeve and thereby non-rotatively 20 lock said roller to said spindle, and a second sleeve on said spindle between the outer end of said first sleeve and the adjacent saddle, said second sleeve being longitudinally 25 movable of but held against rotation with said spindle and the contacting ends of said sleeves being formed with complementary beveled teeth and recesses, and a spring pressing said second sleeve against said first sleeve, whereby said beveled teeth and recesses will serve to hold said spindle against 30 rotation until said interlocking elements upon the roller and spindle become engaged at either end of the line of travel of said roller.

Signed by me, this 22 day of June, 1921. 35
FREDERICK C. SIXT.
